(57) **CLAIM**

The ornamental design for a multi-functional wall mounted storage, as shown and described.

DESCRIPTION

FIG. 1 is a perspective view of a multi-functional wall mounted storage showing my design;

FIG. 2 is a front elevational view;

FIG. 3 is a left side elevational view;

FIG. 4 is a right side elevational view;

FIG. 5 is a top plan view; and,

FIG. 6 is a bottom plan view.

The broken lines showing screws are for the purposes of illustrating environment and form no part of the claimed design.
